UNITED STATES PATENT OFFICE

DAVID J. UHLE AND JOSEPH V. DURNIN, OF ALLENTOWN, PENNSYLVANIA

PULVERIZING OR GRINDING MILL

Application filed November 22, 1928. Serial No. 321,207.

Our invention relates to improvements in pulverizing or grinding mills, and has particular reference to improvements in the grinding ball pushing means or yoke of such mills.

In accordance with our invention, pushing means, preferably in the form of a rotatable yoke is provided, which is secured to and driven by the usual drive shaft. This yoke 10 has outwardly extending arms carrying reciprocatory slidable pusher elements, which have spherically curved convex or forwardly tapered faces, for engaging with the grinding balls, and affording the minimum contacting 15 surfaces between the same. The reciprocatory pusher elements are free to turn upon their axes, and are urged forwardly by yielding means, such as compressible coil springs.

In the accompanying drawings, forming a 20 part of this specification, and in which like numerals are employed to designate like parts throughout the same,

Figure 1 is a central vertical longitudinal section through a mill embodying our invention,

Figure 2 is a horizontal section taken on line 2—2 of Figure 1,

Figure 3 is a similar view taken on line 3—3 of Figure 1,

Figure 4 is a plan view of the yoke and associated elements,

Figure 5 is a side elevation of the same,

Figure 6 is an enlarged fragmentary plan view of one of the rotatable arms of the yoke 25 and the pusher element,

Figure 7 is a side elevation of the same, and,

Figure 8 is a longitudinal section taken on line 8—8 of Figure 1.

The yoke and associated elements constituting the principal feature of the present invention, are particularly adapted for use in connection with the pulverizing or grinding mill, shown in Letters Patent No. 922,468, granted under date of May 25, 1909, to J. W.

Fuller, Jr. The mill embodies generally a casing 10, within which is arranged a grinding ring 11, having a transversely curved annular recess 12, within which travels the grinding balls 14. The upper casing section 50 15 is arranged upon the casing 10, and a screen

16 is disposed within the casing section 15 and spaced therefrom, with a coarser protecting screen 17, disposed inwardly of the first named screen. The pulverized or ground material which passes the screen 16 discharges into a passage 18, and descends through the passage 19 and finally discharges through an outlet 20. The numeral 21 designates a feed hopper, which discharges the material into the upper portion of the casing 15, 60 inwardly of the screen 17.

The numeral 22 designates a vertical drive shaft, journaled in bearings 23 and 24, and driven by a pulley 25. As this construction is identical with that shown in Patent No. 65 922,468, above referred to, it is thought to be sufficient.

Our improved yoke embodies a tubular hub 26, arranged upon the drive shaft 22, to turn therewith. Extending generally radially from the lower end of the hub are spaced horizontal arms 27, integral therewith. These arms have transverse recesses 28, which are preferably cylindrical, and receive bushings 29. Mounted to slide within each bushing is a cylindrical reciprocatory pusher element 30, the outer end of which is convex and spherically curved, as shown at 31, for contacting with the adjacent grinding ball 14. The pusher element 30 not only is free to move longitudinally within the bushing, but is free to turn upon its longitudinal axis. The convex end of the pusher element, which contacts with the grinding ball, is rendered hard by any suitable means. As illustrating 70 75 80 85

one way in which this hardening of the convex face may be effected, we contemplate placing a covering 41 of high speed tool steel upon the pusher element, the same being welded thereto, although the convex face may be hardened by any other suitable means. By virtue of the convex face of the pusher element, the minimum contact surface is afforded between the pusher element and the grinding ball and this permits of the free spinning of the grinding ball. The convex surfaces of the ball and pusher element also permit of the free outward movement of the ball, due to the wearing down of the grinding ring, and the radial movements of the ball, due to the 90 95 100

shifting of the same by different thicknesses of material being ground.

The pusher element 30 is provided with a reduced stem 32 passing through a contracted opening 33 in the arm. This reduced stem provides a shoulder 34. A compressible coil spring 35 surrounds the stem 32 and is arranged within the recess 28, and engages the shoulder 34, to force the pusher element 30 forwardly. A lubricating opening 36 is provided in the top of the arm 27 and is closed by a plug 37.

The stem 32 is provided with a nut 38 or the like to limit the forward movement of the 15 pusher element.

The upper end of the hub 26 of the yoke is preferably beveled, as shown at 43, to deflect material to be ground toward the grinding balls 14. Formed integral with the hub 26 near the upper end thereof are spaced horizontal radial arms 44, arranged at an elevation above the arms 27, and staggered with relation thereto.

The numeral 45 designates a fan or blower 25 as a whole, including a lower ring 46, carrying outwardly projecting radial lugs 47, bolted to the arms 44, as shown at 48. Formed integral with the ring 46 are spaced vertical arms 49, carrying upper vertically arranged 30 blades or paddles 50, integral therewith. The blades 50 are disposed at the leading edges of the vertical arms 49 and are further connected therewith by tapered webs 51, integral therewith. The vertical blades 50 rotate adjacent to the screens 16 and 17 and serve to 35 throw the ground material through or toward the same. The numeral 52 designates lower elevating blades or paddles which are inclined and have their lower ends extending in an elevation beneath the lower ends of the vertical blades 50. The lower elevating 40 blades 52 are preferably provided at their outer edges with upstanding longitudinal flanges 53. The blades 52 are formed integral 45 with the ring 46, and webs 53 reinforce and connect these parts, and are formed integral therewith. The elevating blades 52 operate above and near the grinding balls 14 and serve to raise the powdered or ground material, which is brought into the path of travel 50 of the vertical centrifugal blades 50 and thrown thereby toward the screen 16.

In the operation of the mill, the material is fed into the central portion of the same, 55 through the hopper 21 and passes to the grinding balls 14, traveling upon the grinding rings. The pusher elements, by virtue of their convex faces, have the minimum area of contact with the grinding balls and hence 60 the grinding balls are free to spin during their travel. The pusher elements being spring supported, the shocks or hammering actions are absorbed, particularly upon starting the mill. Further, the yielding support 65 of the pusher element, prevents the breaking

of the yoke arms, carrying the same. Further, the yielding support of the pusher elements, combined with their convex faces, affords a free spinning action for the grinding balls, resulting in the better operation of the 70 mill and the increased life of the grinding balls and associated elements. The shaft 22 is driven at a suitably high speed and the elevating blades 52 serve to draw the ground or powdered material upwardly and through 75 the same into the path of travel of the vertical or centrifugal blades 50, which in turn throw the same toward or through the screens 16 and 17. It is thought that no further detailed description of the operation of the 80 machine is necessary.

It is to be understood that the form of our invention, herewith shown and described, is to be taken as a preferred example of the same, and that various changes in the shape, 85 size and arrangement of parts, may be resorted to without departing from the spirit of our invention, or the scope of the subjoined claims.

Having thus described our invention, we 90 claim:

1. In a grinding mill, a casing, a grinding ring arranged within the casing, a rotatable support arranged within the casing, reciprocating pusher elements carried by the support and having convex faces to engage with the grinding balls, and yielding means to oppose the longitudinal movement of the 95 pusher elements in one direction.

2. In a grinding mill, a casing, a grinding ring arranged within the casing, grinding balls operating upon the grinding ring, a rotatable support arranged within the casing, reciprocating pusher elements mounted upon the support and adapted to turn upon their axes with relation thereto, said pusher elements having convex contact faces, and yielding means to oppose the longitudinal movement of the pusher elements in one direction.

3. In a grinding mill, a casing, a grinding ring arranged within the casing, grinding balls operating upon the grinding ring, a rotatable support arranged within the casing, reciprocating pusher elements mounted upon the support and being permanently free to turn upon their longitudinal axes with relation thereto, and yielding means to oppose the longitudinal movement of the pusher elements in one direction.

4. In a grinding mill, a casing, a grinding ring within the casing, grinding balls engaging the grinding ring, a rotatable support, reciprocating pusher elements mounted upon the support and being permanently free to turn upon their longitudinal axes with relation to the support and having their engaging faces so shaped that they afford the minimum contacting surfaces with the grinding balls, and yielding means to oppose the lon- 130

litudinal movement of the pusher elements in one direction.

5. In a grinding mill, a casing, a grinding ring arranged within the casing, grinding balls operating upon the grinding ring, a drive shaft extending between the grinding balls, a yoke carried by the drive shaft and embodying approximately radial arms having transverse recesses, reciprocatory pusher
- 10 elements mounted within the transverse recesses and being permanently free to turn upon their longitudinal axes with relation to said arms, and springs arranged within the transverse recesses and engaging the pusher
- 15 elements to force them forwardly.
6. In a grinding mill, a casing, a grinding ring within the casing, grinding balls operating upon the grinding ring, a drive shaft extending between the grinding balls, a yoke
- 20 carried by the drive shaft and having radial arms provided with transverse recesses, each recess being open at its forward end and having a bottom wall at its rear end provided with a contracted opening, a reciprocatory pusher element mounted within each
- 25 recess and being permanently free to turn upon its longitudinal axis with relation to its arm, a contracted stem secured to the pusher element and extending through the
- 30 recess and through the contracted opening in the bottom wall, said stem forming a shoulder with the pusher element, a compressible coil spring arranged within the recess and surrounding the stem and confined between
- 35 the bottom wall and said shoulder, said spring being entirely enclosed within the recess, said pusher element being arranged to engage with the adjacent grinding ball, and means to limit the forward movement of the
- 40 pusher element with relation to the arm.

In testimony whereof we affix our signatures.

DAVID J. UHLE.
